UNITED STATES PATENT OFFICE.

WALTER MARSH JACKSON, OF NEW YORK, N. Y.

PRESSURE-REGULATOR FOR AIR, GAS, STEAM, OR LIQUIDS.

SPECIFICATION forming part of Letters Patent No. 389,082, dated September 4, 1888.

Application filed February 7, 1888. Serial No. 263,234. (No model.)

To all whom it may concern:

Be it known that I, WALTER MARSH JACKSON, of New York, in the county of New York and State of New York, have invented certain new and useful Improvements in Pressure-Regulators for Air, Gas, Steam, or Liquids; and I do hereby declare the following to be a full, clear, and exact description of the invention, such as will enable others skilled in the art to which it appertains to make and use the same.

My invention relates to an improvement in pressure-regulators for air, gas, steam, or liquids.

15 The object of my present invention is to provide a pressure-regulator that is of simple construction, and which may be graduated to accurately control the flow of gas, steam, air, or liquids through it, and by its automatic action 20 reduce pressure at the delivery-orifice of the machine to any predetermined degree.

A further object is to produce a liquid, gas, or air pressure regulator which will automatically adjust its valve to control the delivery 25 of fluids passing through it, so as to afford constant pressure of a predetermined degree in a service-pipe that leads the fluid to a point of consumption, compensating instantly for alterations of pressure induced by inequalities 30 in rate of consumption.

With these objects in view my invention consists in certain features of construction and combinations of parts that will be hereinafter described, and pointed out in the claims.

35 Referring to the accompanying drawing, which is a side elevation in section of the device, A represents a tube or pipe, which is bent at A' to produce two vertical legs, A² A³, that are threaded on their upper ends. The 40 leg A³ is shorter than the parallel leg A², and has a chamber, I, of enlarged diameter, attached thereto by its interiorly-threaded lower end, a.

On one side of the chamber I, near its upper 45 end, a tubular outlet, F, is integrally formed, which is tapped to afford screw-thread connection for the pipe F', that leads to the point of consumption, it being the service-pipe into which gas or other fluid is discharged from the 50 pressure-regulator when it is in use.

At the top of the chamber I, preferably con-

centric with its cylindrical wall, an inlet is made, which is threaded on its outer surface for the reception of a cylindrical valve-chest, H, that has a tapped orifice formed at its lower 55 end to engage and form a tight joint with the threaded tubular neck or inlet C, as shown. The free upper end of the annular wall of the inlet C is faced off to produce a true surface or seat, d, the use of which will be explained. 60 An inlet-passage, E, is formed on the side of the valve-chest H, and a supply-pipe, E', is secured thereto by threaded connection or other suitable means. The open top end of the valve-chest H is closed by the removable 65 bonnet H', which is preferably made to have screw-thread connection with the chest.

In the chamber I a cylindrical float, B, is placed. This is open at its lower end and closed at the top, which latter is provided with 70 a stem, c², that extends vertically from a point central to the side wall of the float. The cylindrical inverted cup or float B may be made of metal or other material. Its component material should be of less specific gravity than 75 the liquid, G, which is introduced in the legs A² A³ until a portion of the chamber I is filled, it being important that the fluid should not at any time rise so as to flow through the outlet-opening F.

80 A preferred liquid for use in the bent tube A is mercury, and if it is used the floating cylinder B may be made of sheet metal sufficiently light to float buoyantly.

The top of the tubular leg A² is closed partially by the screw-cap K, which is perforated so as to afford a small air-passage, b, thus breaking the seal over the contained fluid and allowing free atmospheric pressure thereon.

Upon the valve-stem c² a disk-valve, c, is 90 affixed at a proper point above the valve-seat d, the length of the stem being proportioned so as to hold the valve off of the seat when the tubes A² A³ and chamber I are properly charged with mercury or other suitable liquid. 95 A short stem, c³, is made to vertically project from the upper side of the valve c in axial line with the valve-stem c², the upper stem being intended to support in place several weights, D, that are in disk form, perforated to slide 100 over the stem c³ and rest upon and above the valve C.

In order to hold the valve in a vertical position, its lower surface may be furnished with depending wings c' , which radiate at spaced intervals from the stem c'' , to which they are 5 also attached. The side edges of the wings, having loose engagement with the gas-inlet neck c , will hold the valve and float concentric with the cylindrical wall of the chamber A.

When the pressure-regulator is properly 10 connected by the pipe E' to a source of supply—as, for instance, if gas is to be passed through the device to reduce its pressure before consumption—the pipe E' will be attached to a main conduit, the outlet-pipe F' being 15 extended as a house-service pipe to furnish gas for consumption in a dwelling or other building. Now in service the maximum pressure of gas from pipe E' is counterbalanced by the weight of the vertical column of liquid 20 or mercury, G, and the valve C held off of its seat, and to bring the valve closer to its seat a proper amount of weight, D, is placed on it, this graduation of weight being made proportional to the maximum use of gas from the 25 service-pipe F', so as to supply sufficient pressure.

It will be understood from the above description that in no event will the valve C totally close or rest on its seat when the device 30 is adjusted for use as a pressure-regulator.

When the consumption of gas is cut partially off, the pressure on the float B and exposed liquid, G, in chamber I will increase proportionately and the valve C be depressed to adjust just the supply to the consumption. An increase of consumption will diminish pressure above the float and open the valve, these alterations being effected solely by the alternating height of the liquid columns in the tubular legs A^2 A^3 , and consequent change of counterbalance-weight in the outer leg, A^2 .

The pressure-regulator herein described may be used to control the pressure of liquids, whether they are in fluid or gaseous form, and 45 can be arranged to have any desired range of adjustment by proper proportion of its parts for the service, it being adapted to regulate pressure in the largest mains as well as in small service-pipes.

50 Many slight changes in form of the several parts may be made in carrying into effect the

principles embodied in this invention without departure from its legitimate scope; hence I do not wish to limit myself to the exact forms and combinations of parts herein shown; but, 55

Having fully described my invention, what I claim as new, and desire to secure by Letters Patent, is—

1. The combination, with a liquid-holder 60 consisting of two vertical communicating sections, a float-chamber attached to and communicating with one of said sections, a removable perforated cap upon the other section, a valve-chamber in communication with said float-chamber, an inlet-pipe leading to the 65 valve-chamber, and an outlet-pipe leading from the float-chamber, of the inverted-cup-shaped float located within the float-chamber and provided with an upwardly-projecting stem, a valve located within the valve-chamber 70 and attached to said upwardly-projecting stem, and weights adapted to rest upon the stem and valves, substantially as set forth.

2. The combination, with a liquid-holder 75 consisting of two vertical communicating sections, a removable perforated cap on one section, a float-chamber forming an enlarged extension of the other chamber, the upper end of this chamber terminating in a restricted neck the extreme end of which forms a valve-seat, a valve-chamber attached to this neck, an inlet-pipe leading to the valve-chamber, and an outlet-pipe leading from the float-chamber, of a float located within the float-chamber and provided with an upwardly-projecting stem, a valve attached to the stem, and 80 removable weights, substantially as set forth.

3. The combination, with the U-shaped tube, the float-chamber attached to the shorter arm of the tube, and a valve-chamber attached to 85 the upper end of the float-chamber, of the float having the upwardly-projecting stem, and the valve and weights mounted on the stem, substantially as set forth.

In testimony whereof I have signed this 90 specification in the presence of two subscribing witnesses.

WALTER MARSH JACKSON.
